UNITED STATES PATENT OFFICE.

JACOB J. HERB, OF TORONTO, ONTARIO, CANADA.

CLOTHES-WRINGER ATTACHMENT FOR WASHTUBS.

1,348,797.

Specification of Letters Patent.

Patented Aug. 3, 1920.

Application filed November 5, 1918. Serial No. 261,289.

To all whom it may concern:

Be it known that I, JACOB J. HERB, a citizen of the United States, residing at Toronto, Ontario, Dominion of Canada, have 5 invented certain new and useful Improvements in Clothes-Wringer Attachments for Washtubs; and I do hereby declare the following to be a full, clear, and exact description of the invention, such as will enable 10 others skilled in the art to which it appertains to make and use the same.

This invention relates to new and useful improvements in attachments for washtubs, and particularly to attachments to stationary washtubs.

One object of the present invention is to provide a novel and improved device for engagement with one or another of the walls of the tub to protect the same from damage 20 by the clamping screws of a clothes wringer.

Another object is to provide a device of this character which is readily adaptable for engagement over the upper edge of either of the end walls or the central partition wall 25 of a stationary washtub.

Other objects and advantages will be apparent from the following description when taken in connection with the accompanying drawing.

30 In the drawing:

Figure 1 is an elevation of the device in position on the end wall of the tub and which also supports the wringer.

Fig. 2 is an end elevation of the device 35 and the engaging portion of a wringer, the device being partly broken away and the portion of the tub gripped by the device being shown in section.

Referring particularly to the accompanying drawing, 10 represents the end wall of the tub to which my invention is applied. The invention consists of a strip of wood, or other suitable material, which is of the same thickness as the wall of the tub, and 45 is disposed to rest longitudinally on the

upper edge thereof. Secured to each side of the strip of wood 11, are the depending pairs of legs 12 which bear against the side faces of the wall of the tub. Bolts 13 are disposed through the upper ends of the legs 50 and the strip 11 to firmly secure the same to the strip. These bolts are provided with the winged nuts 14 whereby the legs may be firmly clamped against the faces of the wall of the tub.

The clamp members 15 of the wringer 16 are disposed in straddling relation to the wall of the tub and in such position that the two inner members of the clamps engage with the inner legs of the device while the 60 screws 17 of the clamps engage with the other legs, thus thoroughly protecting the faces of the wall of the tub from damage. This is especially useful where the wringer is provided with rather short clamps, which, 65 after constant and continual use would break away the upper edge of the wall. With the present device the clamps of the wringer do not contact with the wall of the tub at any point, thus preventing the inner 70 ends of the screws, of the clamps from biting into the wall.

When a wringer is used which has short clamps which will not reach down to engage the legs of the attachment the clamps are 75 engaged with the opposite side faces of the wooden strip 11.

What is claimed is:

A protecting device for the edge of a washtub comprising an elongated block of 80 a thickness to correspond to the thickness of the edge of the tub, and depending legs secured to opposite sides of the block, adjacent the ends thereof, and in opposite pairs.

In testimony whereof, I affix my signature, in the presence of two witnesses.

JACOB J. HERB.
